UNITED STATES PATENT OFFICE.

JOHN C. BLIEMEISTER, OF BUFFALO, NEW YORK.

BADGE AND PENCIL HOLDER.

1,170,601.

Specification of Letters Patent.

Patented Feb. 8, 1916.

Application filed July 22, 1914. Serial No. 852,381.

To all whom it may concern:

Be it known that I, JOHN C. BLIEMEISTER, a citizen of the United States, residing at Buffalo, in the county of Erie and State 5 of New York, have invented certain new and useful Improvements in Badge and Pencil Holders, of which the following is a specification.

My invention relates to a combined badge 10 and pencil holder adapted to be attached to some part of the wearing apparel and to display the matter printed, stamped, or otherwise placed upon the badge while conveniently retaining the pencil in position.

15 The primary object of my invention is the production of a pencil holder having a badge portion on which may be printed or otherwise displayed an advertisement, or in certain cases to disclose the authority of 20 the person using the same to make collections, inspections and the like.

Another object of my invention is the provision of a device of this kind which is 25 inexpensive and which will retain a pencil in position and at the same time assure the secure fastening of the device to the wearing apparel; the device on account of its inexpensive construction serving admirably as an advertising novelty which can be 30 gratuitously distributed, or given away with purchases of different commodities.

The invention consists in the novel features of construction and in the arrangement and combination of parts to be hereinafter described and more particularly pointed out in the subjoined claims.

Figure 1 is a view showing my improved badge and pencil holder applied to a garment. Fig. 2 is an enlarged vertical 40 section through the device and a portion of a garment, showing the manner in which the pencil is retained within the device and serves to assist in clamping the garment to prevent accidental detachment of the device therefrom. Fig. 3 is a rear view of the 45 device. Fig. 4 is a detached perspective view of the combined pencil retainer and fastening member.

Referring now to the drawings in detail,

like numerals of reference refer to like 50 parts in the several figures.

The device comprises two parts, one a badge or display member 5, and the other a combined pencil retainer and fastening member 6.

55

7 designates a garment to which the device is adapted to be secured.

The badge or display member 5 may be constructed in any suitable manner permitting of the particular attachment thereto of the combined pencil retainer and fastening member herein shown. The preferred construction comprises a disk having a metallic foundation or body portion 8 over the outer face of which a circularly 60 formed piece of celluloid 9 is adapted to be placed, the celluloid serving as the facing member and having the desired information or advertisement printed, stamped or otherwise displayed thereon. The marginal 65 portion of the celluloid is curved around the foundation or body portion 8 and is clamped thereto by a back plate 10, said back plate being formed of resilient material so that it will effectively retain the 70 celluloid facing member in place. Said back plate is provided with a plurality of slits 11 which are arranged at right angles to radial lines, and the metal of the back- 75 ing extending inwardly from said slits is 80 raised, as at 12, to permit one end of the combined pencil retainer and fastening member to be thrust behind the back plate. Although a single slit would be sufficient to provide a practicable device of this kind, 85

I preferably provide a plurality of slits for the reason that when the back plate is placed in position to clamp the marginal portion of the celluloid facing member it will not be necessary to place said back 90 plate in any particular position with reference to the matter displayed on the badge or button.

The combined pencil retainer and fastening member is inserted in the slit 11 95 which will serve to bring the display matter on the badge or button in proper position. The combined pencil retainer and

fastening member is formed of wire coiled at a point near one end, as at 13, the wire being extended from the coil in two stretches, 14, 15, the stretch 15 being rebent upon 5 itself, as at 16, and its extremity pointed, as at 17, so that it serves as a pin. The stretch of wire 15 between the coil and its rebent portion is curved or crooked, as at 18, and this curved or crooked portion lies 10 in contact with the rebent portion 16. The extremity of the stretch of wire 14 is flattened, as at 19, and this flattened portion is adapted to be thrust through any one of the slits 11 in the back plate and be forced 15 inwardly between said back plate and the foundation or body portion 8 of the badge member, as at 20. The flattened portion 19 being securely clamped between said back plate and foundation or body portion 20 prevents turning of the combined pencil 25 retainer and fastening member on the badge member.

When attaching the device to a garment, the rebent or pin portion 16 thereof is thrust 25 through the material of the garment and the crooked or curved portion 18 serves to clamp the material of the garment so that the device cannot accidentally become disengaged therefrom. This clamping tendency of the 30 crooked or curved portion 18 is increased when a pencil is thrust into the device, as shown at 21, the pencil being forced downwardly between the badge member and the stretch of wire 15, the badge member being 35 flexed outwardly on the coil 13 during this action and recovering itself when the pencil reaches the crooked or curved portion 18 in which it is retained, the edge portion 22 of the back plate being in contact with the pencil and being pressed thereagainst by the 40 action of the coil 13. The pencil when positioned within the holder lies at right angles to the combined pencil retainer and fastening member and the proper position of 45 the device is such that said combined pencil retainer and fastening member is always in vertical or substantially vertical position. There is consequently no tendency of the 50 pencil moving lengthwise within the device, as would be the case if said combined pencil retainer and fastening member were arranged in horizontal position.

The device as described is one that can be 55 easily assembled, and attention is invited to the fact that the back plate is curved rearwardly, as at 23, as the metal of the same leaves the foundation or body portion 8. This permits of placing the coil 13, when the parts are assembled, in contact with the 60 outwardly curved portion of the back plate and said curved portion serves as a stop to prevent accidental disengagement of the badge or display member from the combined

pencil retainer and fastening member, it being necessary that the badge or display 65 member be forced outwardly away from the coil, or the coil forced inwardly from the back plate thereof, before the two parts of the device can be separated. Yet the construction is such that the securing end 14 70 of the wire can be easily thrust through any of the slits 11 and into the space between the foundation or body portion 8 and the back plate 10.

Having thus described my invention, what 75 I claim is,—

1. A combined badge and pencil holder comprising a badge or display member, and a combined pencil retainer and fastening member formed of wire fashioned into a 80 coil and having the wire extended in two stretches from said coil, one of said stretches being secured to said badge or display member and the other being directed substantially parallel with said first stretch and re-curved upon itself, the extremity of said re-curved portion being pointed to permit of 85 attaching the device to a garment, said second-mentioned stretch being spaced from said badge or display member to permit of 90 placing a pencil between the two.

2. A combined badge and pencil holder comprising a badge or display member and a combined pencil retainer and fastening 95 member, said pencil retainer and fastening member being formed of wire fashioned into a coil near one end and having a short and a comparatively long stretch of wire extending from said coil, said short stretch of wire being fastened to said badge or display 100 member and said long stretch being re-curved upon itself and having its extremity pointed, said long stretch being further provided with a crooked or curved portion between its re-curved portion and said coil and 105 said crooked or curved portion lying in contact with said re-curved portion.

3. A device of the kind described, comprising a badge or display member having a foundation or body portion and a back 110 plate, said back plate being provided with a slit, and a fastening member formed of wire having one extremity flattened and adapted to be thrust through said slit and be entered and clamped between said foundation or 115 body portion and said back plate.

4. A device of the kind described, comprising a badge or display member having a back plate provided with a plurality of slits arranged in different radial planes, and a 120 fastening member formed of wire adapted to have one end thereof thrust behind said back plate through any one of said slits.

5. A device of the kind described, comprising a badge or display member having a 125 back plate provided with slits arranged in

different radial planes, and a fastening member formed of wire fashioned into a coil near one end to provide a long and a short stretch of wire extending therefrom, said short stretch of wire being flattened at its extremity and thrust behind said back plate through any one of said slits.

In testimony whereof I affix my signature in presence of two witnesses.

JOHN C. BLIEMEISTER.
